UNITED STATES PATENT OFFICE.

ALBERT M. GUILLET, OF CHARLOTTE, NORTH CAROLINA.

ADJUSTABLE PLUG OR SET FOR CENTERING, PLUMBING, OR SETTING SPINDLES.

Application filed November 1, 1922. Serial No. 598,448.

To all whom it may concern:

Be it known that I, ALBERT M. GUILLET, a citizen of the United States, residing at Charlotte, in the county of Mecklenburg and State of North Carolina, have invented certain new and useful Improvements in Adjustable Plugs or Sets for Centering, Plumbing, or Setting Spindles, of which the following is a specification, reference being had to the accompanying drawings.

This invention relates to means for plumbing, setting or aligning perpendicularly and in the exact center of a spinning ring a spindle such as used in spinning cotton or woolen yarn, worsted, silk, flax, mohair, etc., and particularly to what are known as plugs which are adapted to be set over the spindle and which have an enlargement thereon fitting more or less exactly the spinning ring on the ring rail.

In the operation of spinning machines, it is necessary at intervals to note whether the spindles are exactly concentric to the spinning ring on the ring rail so that the spindle may be set or adjusted into perfect alignment with the axis of the ring and absolutely concentric thereto. This has ordinarily been accomplished by the use of an adjusting member in the form of a large bobbin which has a diameter about $\frac{3}{2}$ " smaller than the internal diameter of the spinning ring and which is applied over the spindle to be plumbed while in motion, this adjusting member enabling the workman to determine or note with the eye the exact distance all around between the circumference of the plug and the inner edge of the spinning ring. If the spindle is found not to be in the exact center of the ring the work-

man plumbs the spindle by means of its adjustment at the bottom or sets it so that it will run concentric to the spinning ring, which spinning ring is stationary in the ring rail. This may also be accomplished by placing pieces of paper on either side of the base of the spindle, thus throwing the axis of the spindle in the direction desired.

My invention has for its object the provision of a plumbing or setting device operating on this same principle and embodying a hollow body having the form of an ordinary spindle bobbin, a collar or core fitted permanently upon the hollow body, and a series of bushings of different diameters, all of the bushings being adapted to fit upon and have rotative engagement with

said core or collar, each bushing being readily detachable from the core or collar to permit another bushing to be put in place for the testing of another spindle operating with a different sized ring, these testing or truing devices doing away with the necessity of using a non-adjustable wooden plug or large bobbin and saving the time, labor and expense of having to make an entirely new wooden plug every time the workman has spindles to plumb for a different sized ring. Ordinarily there are upward of fifty different sized rings used in any mill, and my invention contemplates the use of a set of metal bushings for use with each core, these bushings being of a size to fit all the different sized rings used in the mill so that whenever it is desired to true a spindle it is only necessary to place upon the collar the bushing having the proper diameter and then dispose the bobbin upon the appropriate spindle.

A further object of the invention is to so form these bushings as to make the bushing relatively light to thereby cause them to be carried by the spindle and bobbin more easily and with less vibration, which is particularly necessary as spindles are plumbed or trued while running at a standard speed which varies from 8,000 R. P. M. to 10,000 R. P. M.

A still further object is to provide a collar or core so constructed that it may be readily set upon the centering bobbin either at the top, bottom or middle portion of the bobbin, thus permitting the bushing to be disposed upon the bobbin either at the bottom, top or two-thirds up the ring rail traverse.

Other objects will appear in the course of the following description.

My invention is illustrated in the accompanying drawings, wherein:

Figure 1 is a side elevation of a spindle having my improved centering device applied thereto, the ring rail and ring being shown in section;

Figure 2 is a longitudinal sectional view of the centering device, showing one of the larger forms of bushings;

Figure 3 is a plan view of the bushing shown in Figure 2, looking at the under side thereof;

Figure 4 is a sectional view of one of the smaller forms of bushings;

Figure 5 is a fragmentary sectional view

through a collar and bushing having a slightly modified form;

Referring to these drawings, 10 designates a spindle bobbin that suitably fits the spindle to be plumbed. This spindle bobbin, which is of usual form or may be specially made, is tubular so as to fit upon the ordinary spindle and is formed with an enlarged base 11. Mounted upon this bobbin body 10 at any desired point along its length is a core or collar 12 of metal which snugly fits and may be driven upon the plug 10 to any desired point. This core 12 has the lower half of its periphery centrally beveled, as at 13. Above this beveled portion the diameter of the core is reduced and externally screw-threaded, as at 14. Used in connection with this core are a set of bushings 15. These bushings are all alike, in that they are internally screw-threaded, as at 16, to engage the screw-threads 14. When these annular bushings are turned home upon the core, the under face of each bushing adjacent the central screw-threaded aperture fits snugly against the shoulder defining the upper end of the beveled portion of the collar 12.

Relatively large bushings are preferably recessed, as at 17, on their under faces, this recess 17 being concentric to the hub or central portion of the bushings. The small bushings, however, need not be recessed. Except for this difference, all of the bushings are alike, but a set of bushings vary in size so that each bushing is adapted to fit within a standard spinning ring A mounted on a rail B, leaving a space of about $\frac{1}{2}$ " between the inner edge of the ring and the periphery of the bushing.

10 The collars 12 and the bushings 15 may be made of any suitable material, such as wood fiber, aluminum, rubber, wood, etc., and the diameters of the bushings may run from one inch or less in diameter for fine yarns to five inches or greater in diameter for coarse yarns. It will be obvious, of course, that the collar or core 12 may be made of one material and the annular bushing 15 may be made of another material, or that both may be made of the same material.

15 It will be seen that the particular feature of my invention lies in the adjustability of this centering device and the provision of a core or parent plug made to receive a series of bushings or plugs as a guide to plumbing all sizes of spindles or adjusting the same with a result far more accurate than where the old single non-adjustable wooden plug was used. Preferably the top surface of the bushings will be enameled yellow so that they may be readily distinguished from the rings, just as the wooden plug has been heretofore yellowed with chalk for the same purpose.

20 I do not wish to be limited to the recess-

ing of the bushings, as these bushings may be made light in any other suitable manner. The annular recessing of the bushings, however, lightens the plug or bushing and this causes the spindle and bobbin to run more evenly and with less vibration. I do not wish to be limited to threading the bushings on the core, as it is obvious, as illustrated in Figure 5, that these bushings could closely fit onto the core without the use of threads and in this case the cores 12 may be provided with an outwardly projecting peg 18, the bushings being provided with a seat 19 for this peg so as to prevent them being easily turned upon the core. It is obvious that it is within the purview of my invention to use any or all means within the terms of the accompanying claims whereby to receive the bushings on the core and prevent the bushings from being easily turned thereon. My invention makes more perfect work in the plumbing or centering of spindles, is a great convenience, and secures a considerable saving in time, labor and expense.

25 Though I have only shown two sizes of bushings, it is to be particularly understood that a set of bushings will consist of a plurality of bushings having different diameters and that there may be as many bushings in a set as required for ordinary practice, and some sets may run to fifty bushings and some sets to from five to ten bushings, but each of these bushings will have a diameter nearly equal to the interior diameter of a standard ring.

30 In the work of plumbing spindles all the bobbins are removed and a bobbin that fits way down on the spindle snugly and properly is selected or made specially for the purpose. Then the core or collar 12 of my plug is properly fitted thereto so as to secure it firmly in place either at the top, bottom or two-thirds up the bobbin body, and this same testing or centering bobbin with my plug attached at any of the above points mentioned is used for plumbing all the spindles on the spinning frame or such spindles as the bobbin has been originally made to fit.

35 Spindles are plumbed first at the lower end, therefore my plug must be positioned firmly on the lower end of a spindle bobbin or testing bobbin, which is then placed upon the spindle with the ring rail stationary at the bottom of its traverse and the spindle centered with relation to this ring rail. Then when the spindle has been plumbed at the bottom the ring rail is allowed to run to the top of its traverse and by using another testing bobbin or even the same testing bobbin with my plug attached firmly thereto at the top, the spindle is plumbed at the top with relation to the ring rail and so on. This work is termed plumbing spindles top and bottom, but some mills prefer, and

especially on coarse yarns, to have their spindles only plumbed, or as it is usually termed in this case, set, with the ring rail positioned two-thirds up the length of the 5 traverse, and for this purpose my plug would be positioned firmly two-thirds up on the aforesaid bobbin to thereby plumb the spindle with relation to the ring rail. While I have heretofore referred to spinning spindles, it will be understood that my device 10 may be used for plumbing or setting spindles which are used in spooling or twisting yarn, and it is obvious of course that the collar and bushing may be made of any 15 suitable material and constructed in any desired manner.

I claim:-

1. A device for plumbing or truing spinning spindles comprising a tubular body 20 adapted to fit upon the spindle and rotate therewith, and a detachable annular bushing adapted to be applied to said body or removed therefrom, the bushing having a diameter slightly less than but approximating the internal diameter of the spinning ring with which the spindle coacts whereby the bushing will permit the vertical traverse 25 of the spinning ring.

2. A device for plumbing or truing spinning spindles comprising a tubular body 30 adapted to fit upon the spindle and rotate therewith, a collar disposed upon and fitting said body, and an annular bushing adapted to fit upon and rotate with said collar, the bushing having a diameter slightly less than the internal diameter of the spinning ring with which the spindle to be trued coacts.

3. A device for plumbing or truing spinning spindles comprising a tubular body 40 adapted to fit upon the spindle and rotate therewith, a collar disposed upon and fitting said body, and an annular bushing adapted to fit upon and rotate with said collar, the annular bushing and the collar having interlocking means, the bushing having an exterior diameter slightly less than the interior diameter of the spinning ring with which the spindle to be trued coacts whereby the spinning ring may traverse past the bushing.

4. A device for plumbing or truing spinning spindles comprising a tubular body 50 adapted to fit upon the spindle and rotate therewith, an annular collar closely fitting the body and disposable anywhere along the length of the body, and an annular bushing having detachable rotative engagement with said collar having an exterior diameter slightly less than the interior diameter of the spinning ring with which the spindle to be trued coacts.

5. A device for plumbing or truing spinning spindles comprising a tubular body 60 adapted to fit upon the spindle and rotate therewith, an annular collar closely fitting the body and disposable anywhere along

the length of the body, and an annular bushing having detachable rotative engagement with said collar, the annular bushing having an annular recess upon one face the bushing having an exterior diameter slightly less than the interior diameter of the spinning ring with which the spindle to be trued coacts.

6. A device for plumbing or truing spinning spindles comprising a tubular body 70 adapted to fit upon the spindle and rotate therewith, an annular collar fitting tightly upon said body and rotatable therewith, the collar being formed to provide a shoulder and a screw-threaded portion beyond said shoulder, and an annular bushing interiorly 75 screw-threaded to engage the screw-threads of the collar and fit against said shoulder, the bushing having a diameter approximately equal to the interior diameter of the spinning ring with which the spindle to be trued coacts.

7. Means for plumbing or truing spinning spindles comprising a hollow body having the form of a spindle bobbin and adapted to fit upon the spindle and rotate therewith, a collar fitting the bobbin-like body and having an annular seat, and a set of annular bushings having different diameters corresponding to the diameters of standard spinning rings whereby the bushings will 90 permit the usual vertical traverse of the spinning rings, any one of said bushings being adapted to have detachable engagement with the collar for common rotative movement.

8. Means for truing and plumbing spinning spindles comprising a hollow body having the form of a spindle bobbin, the body being formed at one point in its length with an annular seat, and a set of annular bushings having different diameters corresponding to the diameters of standard spinning rings whereby the bushings will permit the usual vertical movement of the spinning rings, any one of said bushings being adapted to have detachable engagement with said seat for rotative movement with the seat.

9. A device for plumbing or setting spinning spindles comprising an annular collar adapted to fit upon a bobbin, and a set of annular bushings having different diameters corresponding to the diameters of standard spinning rings whereby the bushings will permit the usual vertical traverse of the spinning rings, any one of said bushings being formed to have detachable engagement with the collar for rotation therewith.

10. Means for plumbing or setting spinning spindles comprising an annular collar adapted to fit over and have engagement 125 with a bobbin-like body, the collar being exteriorly screw-threaded and having an annular seat, and a set of annular bushings having different diameters corresponding to the diameters of standard spinning rings 130

whereby to permit the vertical traverse of the rings past the bushings and each of said bushings having screw-threaded engagement with the collar.

5. 11. Means for plumbing or setting spinning spindles comprising an annular metallic plug adapted to have detachable engagement with and fit over a bobbin-like body and having a diameter nearly equal to the 10 internal diameter of a spinning ring with which the spindle coacts whereby to permit the usual vertical traverse of the spinning ring relative to the spindle and past the plug.

12. Means for plumbing or setting spinning spindles comprising a member adapted 15 to fit over and be supported by and rotated with a spindle bobbin, said member having an enlargement at one point in its length, the enlargement being circular in plan and having a diameter nearly equal to the internal diameter of the spinning ring with which the bobbin operates.

In testimony whereof I hereunto affix my signature.

ALBERT M. GUILLET.
